UNITED STATES PATENT OFFICE.

BRYSON DEXTER HORTON, OF DETROIT, MICHIGAN, ASSIGNOR TO HORTON-MASSNICK CO., OF DETROIT, MICHIGAN, A CORPORATION OF MICHIGAN.

FUSE-HOLDER.

No. 901,448.

Specification of Letters Patent.

Patented Oct. 20, 1908.

Application filed August 29, 1904. Serial No. 222,565.

To all whom it may concern:

Be it known that I, BRYSON D. HORTON, citizen of the United States, residing at Detroit, in the county of Wayne and State of Michigan, have invented certain new and useful Improvements in Fuse-Holders, of which the following is a specification.

This invention relates to an improvement in fuse holders and the object of the invention is the provision of an indicator, visible from the exterior of the holder, which will at all times indicate the condition of the fuse.

A further object of the invention is the provision of a novel method of securing the fuse to the metallic terminals of the holder.

In the drawings wherein a preferable embodiment of my invention is shown, and wherein like numerals of reference refer to similar parts in the several views, Figure 1 is a longitudinal section of a fuse holder having my improved indicator attached thereto; Fig. 2 is a transverse section of the same; Fig. 3 is a detail view showing the method of securing the fuse strip to the terminals; Fig. 4 is a transverse section of a modified form of my invention; and Figs. 5, 6, 7, 8 and 9 are longitudinal sections of fuse holders showing still other modified forms of my invention.

Referring now more particularly to the drawings A indicates the casing of the fuse holder, B the end caps therefor, C the metallic terminals secured to said caps and projecting within the casing, and D the fuse strip which is secured to the inner projecting ends of the terminals C, and which has a central reduced portion d to define the point at which the same will burn out. The terminals C have their ends stamped out to form the hollow seats c into which the ends of the fuse strip D are adapted to be secured by soldering. The seats c are each provided with side walls c' between which the fuse strip is adapted to fit, and end wall c'' against which the ends of the fuse abut.

From the above described construction it will be seen that in fastening the ends of the fuse strip to the terminals, the bottom, sides and ends of the strip will be soldered to the terminal and solder can then be flowed over the top of the terminal and onto the top of the strip, thereby forming a very efficient joint between the two parts.

E and E' indicate two plates of mica, or other suitable insulating material, which are

provided with slots e and e' to permit them to be strung upon the fuse wire D. The plates E and E' are secured upon the reduced portion d of the fuse strip D.

e² denotes a wire which is connected at one end to the plate E' and at its other end to the interior of the casing A. The wire e² is taut between the plate E' and the casing A.

e³ denotes another wire, the inner end of which is secured to the plate E and the outer end of which passes through an aperture a in the casing and is secured to the free end of a flat spring F secured upon the exterior thereof. The normal tendency of the spring F is to stand away from the outside of the casing, but the wire e³ is of such a length that when it is secured to the free end of the spring F, said spring will be caused to lie flat upon the exterior of the casing A. The wire e³ is preferably secured to a disk f of some suitable material insulated from the end of the spring F which will insulate the indicator spring from the circuit.

From the above described construction it will be seen that as long as the fuse D is in its normal condition, the spring F will lie flat against the outside of the casing, but as soon as the fuse burns out the tension of the spring F will pull the plate E through the molten metal and said spring will assume a position away from the exterior portion of the casing, thereby indicating that the fuse has burned out. The function of the plate E' and the wire e² is to hold the fuse in a central position in the casing A against the tension of the spring F. Without this plate and wire the tension of the spring F might be sufficient to bend the fuse and allow said spring to move away from the casing when the fuse was not burned out.

In the form illustrated in Fig. 4, the casing A is provided with a chamber a² in the side thereof in which slides a piston G, which is provided on its upper side with a stem g. A coil spring H is interposed between the lower side of the piston G and the bottom of the casing, the tendency of which is to raise the piston so that the stem g thereof will project beyond the sides of the casing, and the position of this piston will indicate the rupture of the fuse. The piston is however normally confined within the chamber a², against the tension of the spring H, by the wire e³ which has its end secured to the piston G and the plate E secured on the fuse strip D. The

strip E' and wire e² are the same in this form as in the form described in Fig. 1.

In Fig. 5 I have shown a single wire e⁴ which is secured at one end to the inner side 5 of the casing A and is then wrapped around the fuse strip D several times to properly position the same in the casing and then has its free end passed through the aperture a in the casing and secured to the free end of the 10 spring F secured upon the exterior thereof. In this form when the fuse burns out the tension of the spring will cause the portion of the wire e⁴ wrapped around the fuse strip D to cut through the melted portion thereof 15 and unwind a sufficient amount to permit said spring F to assume a position away from the casing A.

In Fig. 6 I have shown the form of indicator employed with wire fuses. In this 20 form the wire fuse D has its central portion bent in the form of an S. The wire e⁵ connects one loop of the S with the casing A and another wire e⁶ is connected to the other loop of the S and extends through the aperture a 25 in the casing and is secured to the free end of the spring F secured upon the exterior surface thereof.

In the form shown in Fig. 7 a fusible wire e⁷ is secured at one end to the inside of the 30 casing A and extends through an aperture d' formed in the fuse strip D and through an aperture in the casing and has its free end secured to the free end of a spring F secured upon the exterior surface of the casing, the 35 wire e⁷ being of such a length that the spring F will be caused to lie flat against the side of the casing. In this form the fusion of the strip D will take place at the point where the opening d' is located, that being the portion 40 of the strip having the smallest cross-section of metal, and as the wire e⁷ extends through the opening d' it will be fused at the same time as the strip D and the spring F will assume a position away from the outside of the 45 casing, thereby indicating that the fuse has burned out.

In Fig. 8, I have shown a device somewhat similar to that shown in Fig. 5, except that the wire is passed through a hole d² in the 50 strip and then wrapped around the strip by giving the same one turn after said wire has been passed through. The ends of the wire are secured as in Fig. 5, the one to the casing and the other to the free end of the spring F.

In Fig. 9, I have shown another form of indicator which may be used with wire fuses. In this form the S bends in the wire extend 55 longitudinally instead of transversely and but a single wire e⁸ is used instead of two 60 wires as in the form shown in Fig. 5. The wire e⁸ is passed through one of the loops in the fuse wire and has its ends secured respectively to the free end of the spring F and the side of the casing in advance of said loop, 65 thereby causing the wire to assume an an-

gular position in the casing. When the fuse burns out the tendency is for the wire to straighten out, thereby permitting the spring to assume a position away from the casing.

In all the forms which I have described 70 the casing may or may not be filled with some finely divided non-conducting material.

I do not desire to limit myself to the precise form and construction shown in the 75 drawings as it is obvious that many minor changes might be made thereto without departing from the spirit of the invention.

Having thus described the invention what is claimed as new and desired to be secured 80 by Letters Patent is:—

1. In a fuse holder, a casing, a fuse therein, a spring secured to the exterior of the casing, and a transverse connection between said spring and the fuse serving to hold the spring 85 in contact with the exterior of the casing while the fuse therein is unbroken.

2. The combination with a fuse holder having a fuse therein, of a flat spring secured to the exterior of the holder, and a wire secured to the free end of the spring and the 90 fuse.

3. The combination with a fuse holder having a fuse therein, of a flat spring secured to the exterior of said holder, the free end of 95 said spring being provided with an insulated portion, and a connection between the fuse and the insulated portion of the spring.

4. The combination with a fuse holder having a fuse therein, of a spring actuated 100 indicator secured to the holder, and a wire provided at one end with a loop encircling the fuse and having its other end secured to the indicator.

5. The combination with a fuse holder 105 having a fuse therein, of a spring actuated indicator secured to the holder, and a wire provided at one end with a plate of insulating material encircling the fuse and having its other end secured to the spring actuated 110 indicator.

6. The combination with a fuse holder having a fuse therein, of a spring actuated indicator secured to the holder on one side 115 thereof, a connection between the indicator and the fuse and a connection between the fuse and the opposite portion of holder.

7. The combination with a fuse holder having a fuse therein, of a spring actuated indicator secured to one side of the holder, a 120 connection between said indicator and the fuse, and a connection between the fuse and the opposite side of the holder.

8. The combination with a fuse holder having a fuse therein, of a spring actuated 125 indicator secured to the holder, a wire secured at one end to the indicator and at its other end to the fuse, and a second wire secured at one end to the holder and at its other end to the fuse.

9. The combination with a fuse holder comprising a casing and a fuse secured therein, of a spring actuated indicator secured to one side of the casing, a wire provided at one end with an insulated plate encircling the fuse and having its other end secured to the indicator, and a connection between the fuse and the opposite side of the casing. 45
10. The combination with a fuse holder comprising a casing and a fuse secured therein, of a spring secured at one end to the exterior of the casing on one side thereof, a connection between the free end of the spring and the fuse, and a connection between the fuse and the opposite side of the casing. 50
11. The combination with a fuse holder comprising a casing and a fuse secured therein, of a spring secured at one end to the exterior of the casing, a wire provided at one end with an insulated plate secured to the fuse and having its other end secured to the free end of the spring, and a second wire provided at one end with an insulating plate secured to the fuse and having its other end secured to the opposite side of the casing. 55
12. In a fuse holder, a casing, a fuse therein, having a weakened portion, a movable indicator secured to the exterior of the casing, and a connection between the indicator and the weakened portion of the fuse. 60
13. In a fuse holder, a casing, a fuse therein having a weakened portion, a spring actuated indicator secured to the exterior of the casing and a transverse connection between the spring actuated indicator and the weakened portion of the fuse. 65
14. The combination with a casing or holder having end terminals and an inclosed fuse having its ends attached to the casing terminals of a spring actuated indicator upon the outside of the casing, and a wire that projects through the side of the casing and has its respective ends attached to the indicator and to an intermediate portion of the fuse. 70
15. The combination with a casing having end terminals and an inclosed fuse interposed between said terminals, of a spring-actuated indicator on the outside of the casing and a wire that projects through the side of the casing and has its respective ends attached to the free end of the indicator and to substantially the middle point of the fuse. 75
16. In an inclosed fuse or cut out, a casing having an aperture through its side wall, an internal fuse wire attached at its ends to the casing, an external spring-acting finger attached at one end to the casing, and a connection between the opposite end of said finger and fuse wire, passing through said aperture, for holding said finger under tension. 80
17. The combination with a casing having end terminals and a fusible strip within the casing and connected to the end terminals, of a spring-actuated indicator supported exteriorly upon the side of the casing and a wire having its respective ends so attached to the indicator and to an intermediate point in the fusible strip as to exert a lateral strain thereon. 85
18. In a fuse holder, a casing, a fuse therein, a spring secured exteriorly of the casing, and a transverse connection between said spring and the fuse serving to hold the spring adjacent the exterior of the casing while the fuse therein is unbroken. 90

In testimony whereof I affix my signature in presence of two witnesses.
